ASSEMBLED ENGINE PISTON

Frederick Elder, Valley City, Ill.

Application June 6, 1939, Serial No. 277,698

2 Claims. (Cl. 309—15)

This invention aims to provide a novel piston for internal combustion engines and the like, so constructed that it may be taken down readily, to permit the cleaning of the spacers that are interposed between the piston rings, to permit a renewal of the rings, and for like purposes.

A further object of the invention is to provide a piston of the class described wherein a connector, to which the piston rod is pivoted, serves to hold assembled, the body of the piston and a sleeve which cooperates with the body.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Figure 1 shows in longitudinal section, a device constructed in accordance with the invention;

Figure 2 is a transverse section on the line 2—2 of Figure 1.

Fig. 3 is a fragmental transverse section, showing the body and the sleeve telescoped, to shorten the piston for storage and shipment.

The piston forming the subject matter of this application comprises an inverted cup-shaped body 1 having an outstanding flange 2 defining a shoulder 3, a sleeve 4 being disposed about the body, the inner end of the sleeve defining a shoulder 5, the body and sleeve having registering openings 6, a connector, to which the piston rod is pivoted, being engaged in the openings, to hold the body and sleeve assembled.

The connector, which joins the piston rod to the piston, may be of any desired form. In the form shown in Figure 1, the body 1 and sleeve 4 are held together by bushings 7, located in the openings 6, a wrist pin 8 having its end portions received in the openings. Without a specific showing in the drawing, it will be understood that the bushings 7 may be omitted, if the wrist pin 8 is of proper diameter, the term "connector" being used to cover either that form or the one delineated in Figure 1.

The shoulder 2 is recessed to receive a pack-

ing ring 9, which is L-shaped in cross section. The shoulder 5 is recessed to receive a packing ring 10 which, also, is L-shaped in cross section. Between the rings 9 and 10 are disposed any desired number of annular packing rings 11. Spacers 12, which are L-shaped in cross section, are interposed between the packing rings and engage the shoulders 3 and 5, the spacers having contact with each other, longitudinally of the piston, as shown in Figure 1.

The construction is such that the piston may be taken down readily, by removing the connector 8—1, and either the packing rings or the spacers may be renewed, and the spacers may be cleaned and put back if necessary. The cleaning out of carbon is facilitated, and the sticking together of parts is avoided. The construction is such that the entire device may be taken apart and put together readily, without damage to any of its constituent members.

The external surface of the body 1 and the internal surface of the sleeve 4 are smooth, whereby the body and the sleeve can be telescoped until the shoulders 3 and 5 contact, to shorten the piston for storage and shipment. The packing means which is interposed between the shoulders 3 and 5 serves to align the openings 6 of the body 1 and the sleeve 4, to receive the piston rod connector. The bushings 7 of the piston rod connector hold the body 1 and the sleeve 4 together, prior to the insertion of the wrist pin 8.

What is claimed is:

1. A piston for internal combustion engines and the like, comprising an inverted cup-shaped body having an outstanding shoulder, a sleeve about the body, the inner end of the sleeve defining a shoulder, the external surface of the body and the internal surface of the sleeve being smooth, whereby the body and the sleeve can be telescoped until the shoulders contact, to shorten the piston for storage and shipment, the body and the sleeve having transverse openings, packing means located between the shoulders and aligning the openings of the body and the sleeve, and a piston rod connector engaged in the openings to hold the body and the sleeve assembled.

2. The piston of claim 1, wherein the connector comprises bushings in the openings, and a wrist pin in the bushings, the bushings holding the body and the sleeve together, prior to the insertion of the wrist pin.

FREDERICK ELDER.
